UNITED STATES PATENT OFFICE.

ALBERT HABERSTROH, OF BOSTON, MASSACHUSETTS.

ART OF MAKING STENCILS.

SPECIFICATION forming part of Letters Patent No. 628,815, dated July 4, 1899.

Application filed February 13, 1899. Serial No. 705,418. (No model.)

To all whom it may concern:

Be it known that I, ALBERT HABERSTROH, a citizen of the United States, residing at Boston, in the county of Suffolk and State of Massachusetts, have invented new and useful Improvements in Modes of Making Stencils, of which the following is a specification.

This invention relates to improvements in modes of making stencils of the kind that are to be used for stenciling walls, ceilings, fabrics, &c., or other surfaces that are desired to be decorated, and it is carried out as follows, reference being had to the accompanying drawings, wherein—

15. Figure 1 represents a top plan view of my improved stencil, and Fig. 2 represents a cross-section on the line 2 2, shown in Fig. 1.

Similar letters refer to similar parts wherever they occur on the different parts of the drawings.

In making my improved stencil I proceed as follows: I first take a porous or perforated sheet A, which I term the "base," preferably made of textile or fibrous material, or, if so desired, fine woven wire-netting may be used as a material for such base. To such porous perforated base I apply a suitable filling B, soluble in water. As a material for such filling I use any suitable paint or plastic composition, soluble in water, which I cause to be impregnated or molded between the meshes of the porous or perforated base, so as to be firmly attached thereto. In using such paint or plastic material as a filling it may be applied to the perforated or porous base by means of a brush or spatula or similar tool,

according to the nature and consistency of such filling. After such soluble filling is dry or has become set I cover such portions of the filling that are to remain affixed to the 40 base with suitable paint or composition, non-soluble in water, and after such paint has become dry I wash the stencil with water, causing the non-painted portions thereof to be dissolved and washed away, leaving the perforated or porous base bare at such washed-away portions, thus producing a stencil which may be used for the purpose of applying coloring or plastic material to walls, ceilings, fabrics, or other surfaces that are to be decorated. 45 50

What I wish to secure by Letters Patent and claim is—

The herein-described method of making stencils, which consists in impregnating a 55 fo- raminous base with a filling of paint soluble in water, allowing the same to dry, then cov- ering portions of such filling with a water- proof paint non-soluble in water, allowing the same to dry and finally washing the same with 60 a liquid to dissolve the non-painted portions and removing the same, leaving the base at such washed-away portions bare, substan- tially as specified.

In testimony whereof I have hereunto set 65 my hand in presence of two subscribing wit- nesses.

ALBERT HABERSTROH.
